PISTON FOR INTERNAL COMBUSTION ENGINES

Auguste Louis René Bernard, deceased, late of
Rueil-Malmaison, France, by Renée Bernard,
née Bournonville, executrix, Paris, France

Application December 17, 1934, Serial No. 757,977
In Belgium December 22, 1933

13 Claims. (Cl. 123—176)

The present invention relates to pistons for internal combustion engines, and it is more especially, although not exclusively, concerned with pistons provided with a projection against which 5 is directed and impinges the jet from an injector.

The object of the present invention is to provide a piston which is better adapted to meet the requirements of actual practice.

The essential feature of the present invention 10 consists in providing a piston with means, located under the piston head and extending between the central portion of said piston head and the piston skirt, for shoring up said piston head.

Another feature of the invention consists in 15 providing an annular cushion of a compressible material, such for instance as a compressed metallic powder, under the peripheral portion of the piston head and upon the upper portion of the skirt of said piston.

20 Other features of the present invention will result from the following detailed description of some specific embodiments thereof.

Preferred embodiments of the present invention will be hereinafter described, with reference 25 to the accompanying drawings, given merely by way of example, and in which:

Fig. 1 is an axial section view of a piston according to the present invention;

Fig. 2 is an axial section view of another embodiment of the piston according to the present invention, also showing the walls of the cylinder in which said piston is fitted and the combustion chamber;

Fig. 3 is a sectional view of another embodiment of the piston;

Fig. 4 is a view similar to Fig. 2, showing still another embodiment of the piston according to the present invention.

According to the present invention, and as 40 shown by the drawings, relating to several embodiments of the invention, there is provided, below piston head 1 and between the central portion of said piston head and the peripheral walls, or skirt, of said piston, means for shoring up said piston.

Preferably, these means are so devised as to support the piston head along an annular zone thereof, and these means are themselves supported, along the circumference of the piston 50 skirt, by an annular projection 2 carried by said piston skirt, either below the zone carrying the packing rings, as in the embodiments of Figs. 2 and 4, or at least below the upper packing rings, as in the embodiments of Figs. 1 and 3.

55 For this purpose, in the embodiments of Figs.

1 and 4, the inner face of piston head 1 is provided with a tubular part 3 extending inwardly, and preferably coaxially, in said piston. This tubular part 3 bears against a kind of partition 4 itself supported by annular part 2 of the piston skirt, either directly, as shown by Figs. 1 and 4, or indirectly, as shown by Fig. 2. Advantageously, partition 4 is cup-shaped and its convexity is turned toward the piston head 1.

Of course, the arrangement above described is 10 applicable as well in the case in which the piston head is made of several parts, consisting of different metals, as shown by Fig. 1, as in the case in which said piston head is made of a single part, as shown by Figs. 2 to 4.

15 In the embodiments shown by Figs. 2 and 3, the means, interposed between the piston head and the piston skirt, for shoring up the central part of said piston consist of a single piece 5, of annular structure in the embodiment of Fig. 3, or 20 of solid structure, as in the embodiment of Fig. 2, bearing at the top against an annular zone of the inner face of the piston head, and at the bottom against annular part 2 carried by the piston skirt. In the embodiment of Fig. 2, piece 5 is made of a 25 light weight metal for instance, and its lower bearing portion or shoulder 5' is interposed between the partition 4 and the annular part 2, while in the embodiment of Fig. 3 piece 5 is advantageously made of steel.

30 It will be readily understood that, with either of the embodiments above described, the arrangement according to the present invention makes it possible to considerably reduce the weight of the piston head since it prevents sagging thereof 35 under the effect of the high pressures that are applied thereon.

35 This advantage is particularly important in the case of internal combustion engines in which the piston head is provided with a substantially conical projection 6 (Figs. 2 and 4) adapted for instance to penetrate into a tore-shaped compression chamber 7 and upon the top of which is directed and impinges the jet from injector 8.

40 As a rule, in this case, the piston head has the approximate shape of a cone having concave generatrices and which therefore is not well adapted to resist crushing stresses.

45 Furthermore, piston heads of this kind must be made of a material, such as a special steel, 50 which is capable of withstanding very high temperatures, and, as a rule, such a material has very bad mechanical properties, especially at the temperatures at which it is caused to work. However, owing to the provision of the means for 55

shoring up the central part of the piston head as above described, it is not necessary to have piston heads of very great thickness.

Furthermore these means for shoring up the central part of the piston head constitute a supplementary way for the outflow of the heat transmitted to the piston head.

Of course, said means may be established either in a continuous form, for instance by making use 10 of a tubular partition, so as to provide between said means and the peripheral part of the piston head a closed chamber 9, or in a discontinuous form if said chamber 9 communicates with the inside of the piston through apertures.

15 The arrangement above described may also include the following feature, which further increases the advantages above referred to.

According to this feature, there is provided an annular cushion of a compressible material which 20 is a good conductor of heat, such as slightly compressed metallic powder, under the peripheral portion of the piston head and against the upper portion of the piston skirt.

If the piston is made as above described, this 25 cushion shall advantageously be placed in chamber 9, which will then be tightly closed, as shown in the embodiments of Figs. 1, 2 and 4.

This cushion, which may for instance consist 30 of aluminium powder sufficiently compressed in order that its density may range between 1.6 and 1.8, will further insure, besides fluid tightness of the joints in the piston, a good thermic contact of the various elements of said piston, whether their coefficients of dilatation are substantially 35 equal or not, and finally a better flow of the heat toward the portions of the piston skirt located below the zone carrying packing rings 10, and especially the upper packing rings.

In the particular case of pistons provided with 40 the conical projection 6 above referred to, the annular cushion of metallic powder has the further advantage of making it possible to keep the central portion of the piston head (therefore projection 6) at a temperature sufficiently high for 45 ensuring a good working of the engine. As a matter of fact, this temperature must generally be substantially higher than the temperature of the peripheral portion of the piston head.

The latter shall therefore be cooled in the best 50 possible manner and the packing rings will be protected in a satisfactory manner against the action of heat, in spite of the high temperature of the central zone of the piston.

Although the characteristic features that have 55 been described may be carried out in many ways, and independently of one another, I have found that it is advantageous to combine them as shown in the embodiment of Figs. 2 and 4, as it will be hereinafter explained.

60 A tubular element 11, adapted to play the part of a piston skirt and provided with packing rings 10, is made of any suitable metal, such for instance as cast iron.

In the lower part of this piston skirt is inserted 65 a kind of sleeve 12, advantageously made of two symmetrical parts, each carrying a projection 13¹, 13² respectively, said projections being engaged in a tube 14, which constitutes the gudgeon pin of the piston.

70 On the inner wall of skirt 11 is provided an annular shoulder 15 against which is applied the upper edge of sleeve 12 when the latter is held in position as shown in Fig. 4 by an annular nut 16 which is screwed into skirt 11 from the bottom thereof, or by screw threads 16' on the outer

wall of sleeve 12 cooperating with similar threads at the inner wall of skirt 11, as shown by Fig. 2.

The head 1 of the piston is made of special steel and its central part is provided with the projection 6 above referred to. On the inner side, said central part of the piston head is further provided with tubular part 3.

Means are provided for assembling by screwing the piston head 1 with the piston skirt 11, said means consisting for instance of an annular nut 10 10 17, according to Fig. 4, or of cooperating screw threads 17', according to Figs. 2 and 3.

A frusto-conical piece, for instance of steel, constitutes the partition 4 above mentioned. This piece is provided at its lower end with a 15 cylindrical edge or flange 18, of bevel-shaped section, adapted to be inserted with a force fit in said skirt 11, above shoulder 15. At the other end, said part 4 is provided, around the central hole with which it is provided, with another cy- 20 lindrical edge 19, analogous to the above mentioned one, and adapted to fit with a force fit around the tubular part 3 above referred to.

After piston head 1 has been fixed in position on piston skirt 11, a sufficient amount of aluminium powder is poured (after having placed the piston upside down) into the annular space existing between part 3 and the top of the piston skirt, and partition 4 is forced into the position shown in the drawings, thus compressing and enclosing 30 in chamber 9 said metallic powder.

If the various elements of the piston to be made have been suitably devised, and especially, if the amount of metal powder is exactly measured and compressed, the lower edge of partition 4 is final- 35 ly exactly flush with the edge of shoulder 15 as shown by Fig. 4, or with the upper edge of bearing portion or shoulder 5', according to Fig. 2.

If desirable, special means may be provided for keeping said partition in position, on the one 40 hand with respect to piston head 1 and on the other hand with respect to the piston skirt 11.

For instance, according to Fig. 4, an annular nut 20 is first screwed in the central hole of element 4, said annular nut being adapted to butt 45 against the lower edge of part 3, whereby, after assembling of the parts, the piston head is suitably supported by element 4.

On the other hand, a second nut 21 is subsequently screwed inside part 3 in such manner 50 that, after tightening, the head of this annular nut is applied, eventually with the interposition of a suitable packing member, against the head of the above mentioned nut 20, which completes the fixation in both directions of part 3 and element 4.

Finally the sleeve 12 that has been above described is inserted in position, and the assembling of the parts is completed by screwing nut 16, the upper edge of sleeve 12 being applied 60 against shoulder 15 and, according to Fig. 4, also against the lower edge of element 4, so as to constitute the annular projection 2 mentioned at the beginning of this description.

While I have, in the preceding description, disclosed what I deem to be practical and efficient embodiments of the present invention, it should be well understood that I do not wish to be limited thereto as there might be changes made in the arrangement, disposition and form of the 70 parts without departing from the principle of the present invention as comprehended within the scope of the appended claims.

What I claim is:

1. A piston for an internal combustion engine 75

which comprises, in combination, a piston head, a piston skirt attached to said piston head, a tubular part rigid with the central part of the piston head and extending inwardly from the inner face thereof, an annular projection on the inner cylindrical wall of said piston skirt, a frusto-conical piece bearing at its larger end against said annular projection, a cylindrical part rigid with said end of said piece mounted 5 with a force fit in said piston skirt, a cylindrical part rigid with the smaller end of said piece, and mounted with a force fit around said tubular part rigid with said piston head, and means carried 10 by the last mentioned cylindrical part for bearing against the edge of said tubular part.

2. A piston according to claim 1 in which the last mentioned means consist of an outwardly threaded annular nut screwed in the last mentioned cylindrical part and adapted to butt 20 against the edge of said tubular part.

3. A piston according to claim 1 in which the last mentioned means consist of an outwardly threaded annular nut screwed in the last mentioned cylindrical part and adapted to butt 25 against the edge of said tubular part, further including an outwardly threaded annular nut screwed in said tubular part carried by said piston head, and a flange carried by the last mentioned nut adapted to bear upon the annular 30 edge of the first mentioned nut.

4. A piston according to claim 1 further including a compressed metal powder filling the closed space limited by said frusto-conical piece, the peripheral portion of said piston head, and the upper part of said piston skirt.

5. In an internal combustion engine, a piston comprising in combination a piston head having an upward projection at the center thereof, a piston skirt secured to said piston head, and an annular body of compressed heat-conducting metallic powder arranged below and in contact only with that portion of the piston head adjacent the base of said projection.

6. In an internal combustion engine, a piston comprising in combination a piston head having an upward hollow conical projection in the center thereof, a piston skirt secured to said piston head and an annular body of compressed heat-conducting metallic powder arranged below and in contact only with that portion of the piston head adjacent the base of said projection.

7. A piston for an internal combustion injector engine comprising in combination a piston head having an upward projection at the center thereof adapted to receive a fuel jet which is directed to impinge upon the top of said projection, a piston skirt secured to said piston head, an annular body of compressed heat-conducting metal-

lic powder arranged below and in contact only with that portion of the piston head adjacent the base of said projection.

8. In an internal combustion engine, a piston comprising in combination a piston head having an upward projection at the center thereof, a piston skirt secured to said piston head adjacent the base of said projection, a tubular part secured to said projection adjacent the base thereof and extending downwardly therefrom toward the inside of said piston head, and an annular body of compressed heat-conducting metallic powder surrounding said part.

9. In an internal combustion engine, a piston comprising in combination a piston head having an upward hollow conical projection in the center thereof, a piston skirt secured to said piston head, an annular wall secured to said projection adjacent the base thereof and extending downwardly therefrom toward the inside of said piston head and forming a chamber therein, a transverse wall closing said chamber at the lower end, and an annular body of compressed heat-conducting metallic powder within said chamber surrounding said annular wall.

10. In an internal combustion engine, a piston comprising in combination, a piston head, an upward projection at the center of said piston head, a piston skirt extending downwardly from said head, and means for shoring up said piston head comprising at least one element extending downwardly from said piston head adjacent the base of said projection and secured to said piston skirt, said element, said piston head, and said skirt forming a closed annular chamber therebetween, and compressed metallic powder within 35 said chamber.

11. A piston comprising a head having at its center an upward projection, a skirt extending downwardly from said head, a member extending downwardly from said head adjacent the base of said projection, and an annular body of compressed heat-conducting metallic powder surrounding said member.

12. A piston comprising a head having at its center an upwardly extending portion, and an annular body of compressed metallic powder in contact only with the portions of the piston outside the vertical projection of said upwardly extending portion.

13. A piston comprising a head having at its central portion an upward projection, and a body of compressed metallic powder arranged in contact only with portions of said piston other than said central upward projection.

RENÉE BERNARD, NÉE BOURNONVILLE,
Executrix of Auguste Louis René Bernard, De-
ceased.
